Albert R. Morrison
INVENTOR
BY Victor J. Evans
ATTORNEY

UNITED STATES PATENT OFFICE

ALBERT R. MORRISON, OF WINDSOR, CONNECTICUT

REEL-SWIFT BRACE

Application filed November 27, 1929. Serial No. 410,177.

My present invention has reference to a device for the unwinding of skeins of silk, rayon, cotton, wool or other textile material, and is of the type commonly known among manufacturers as a "swift".

Swifts are constructed of wood to include a hub having spaced pairs of spokes or pegs extending angularly therefrom and in the general construction there is wound around 10 and connected to the pairs of spokes or pegs a small loop of string near the top of such spokes or pegs and around which the silk, rayon, is wound. This construction does not permit of the spreading of the material but 15 rather bunches the same so that the same cannot be readily unwound from the swift and frequently results in the breakage of the skeins. It is, therefore, my primary object to provide cross members having 20 yieldable spring means for connecting the same to the spokes of the swift and which members are arched outwardly so that the skeins of silk, etc., will be directed from the center to the sides thereof, the said means also 25 having flanged ends to prevent the material from contacting with the pegs or spokes.

To the attainment of the foregoing the invention consists in the improvement herein-after described and definitely claimed.

30 In the drawings:

Figure 1 is a side elevation of a swift provided with the improvement.

Figure 2 is an end view thereof.

Figure 3 is a side elevation of one of the 35 cross or connecting pieces for the spokes or pegs of the swift.

Figure 4 is a top plan view thereof.

Figure 5 is a sectional view on the line 5—5 of Figure 3.

40 The swift, as usual, is constructed wholly of wood and includes a hub 1 from whose ends there radiate spokes or pegs 2. The spokes or pegs are round in cross section and preferably decrease in thickness from their outer 45 to their inner or connected ends.

The cross spreader pieces for the skeins of material which form the improvement are preferably formed of metal and as disclosed by the drawings are each substantially U-shaped in cross section. Each member is

indicated by the numeral 3. Each of the members 3 is arched, or in other words, is inclined in opposite directions from its center to its ends. The ends of each of the members 3, on the outer edge thereof, are formed with an outwardly extending flange 4 and the said ends of the spacer and spreader members 3 have fixed thereon outwardly extending coil springs 5. These springs are designed to be arranged over the spokes or pegs 2 and to frictionally contact therewith so as to permit of the adjustment of the members 3 on the spokes. The members 3 are arched outwardly with respect to the hub of the swift and by such arrangement it will be apparent 55 that the skeins of material wound there-around will be directed from the center to the flanged ends of the member 3 with the result that such material cannot become bunched or knotted and may be readily unwound from 60 the swift.

The simplicity of the construction and the advantages thereof will, it is thought, be readily apparent but obviously I do not wish to be restricted to the precise details herein 65 set forth and, therefore, hold myself entitled to make such changes therefrom as fairly fall 70 within the scope of what I claim.

Having described the invention, I claim:

In combination with a swift which includes 80 a hub having spaced pairs of radial pegs extending therefrom, of cross sectionally U-shaped outwardly arched members arranged between each pair of pegs, said members having their ends formed with outwardly extending flanges, and coil springs fixed on the ends of the said members to be arranged over and to frictionally engage with the pegs of the 85 swift.

In testimony whereof I affix my signature. 90

ALBERT R. MORRISON.
